(57) **CLAIM**

We claim the ornamental design for an attachment mechanism, as shown and described.

DESCRIPTION

FIG. 1 is a top view of an attachment mechanism of a band portion of a wearable fitness monitor.

FIG. 2 is a bottom view of the attachment mechanism of FIG. 1.

FIG. 3 is a front view of the attachment mechanism of FIG. 1.

FIG. 4 is a back view of the attachment mechanism of FIG. 1.

FIG. 5 is a side view of the attachment mechanism of FIG. 1.

FIG. 6 is the other side view of the attachment mechanism of FIG. 1.

FIG. 7 is an isometric view of the attachment mechanism of FIG. 1.

FIG. 8 is an isometric view of the attachment mechanism of FIG. 1; and,

FIG. 9 is an isometric view of the attachment mechanism of FIG. 1 mounted in a band.

Stipple shading is used in all of the accompanying Figures to convey surface contouring and not texture. The broken lines shown in the drawings illustrate portions of the attachment mechanism that form no part of the claimed design. Surfaces that do not include stipple shading and are bounded, at least in part, by broken lines form no part of the claimed design.
